UNITED STATES PATENT OFFICE.

WILLIAM SCHNELL, OF DETROIT, MICHIGAN, ASSIGNOR TO TERNSTEDT MANUFACTURING COMPANY, OF DETROIT, MICHIGAN, A CORPORATION OF MICHIGAN.

DESIGN FOR A LATCH FOR A REFRIGERATOR.

Application filed February 4, 1929. Serial No. 29,899. Term of patent 7 years.

To all whom it may concern:

Be it known that I, WILLIAM SCHNELL, a citizen of the United States, residing at 5571 Clarendon Avenue, Detroit, in the county of Wayne and State of Michigan, have invented a new, original, and ornamental Design for a Latch for a Refrigerator, of which the following is a specification, reference being

made to the accompanying drawings, forming part thereof.

Fig. 1 is a front elevation of the latch.

Fig. 2 is a plan view of the same.

I claim:

The ornamental design for a latch for a refrigerator substantially as shown.

WILLIAM SCHNELL.
